UNITED STATES PATENT OFFICE.

SILAS WEST, OF HAVERHILL, MASSACHUSETTS.

DESIGN FOR A SIGN-BOARD.

SPECIFICATION forming part of Design No. 27,057, dated May 18, 1897.

Application filed March 16, 1897. Serial No. 627,888. Term of patent 7 years.

To all whom it may concern:

Be it known that I, SILAS WEST, a citizen of the United States, residing at Haverhill, in the county of Essex and State of Massachusetts, 5 have invented and produced a new and original Design for a Sign-Board, of which the following is a specification, reference being had therein to the accompanying drawings.

In the accompanying drawings, Figure 1 is 10 a face view of a sign-board, illustrating my design; and Fig. 2 is a view in cross-section on the line 2 2 of Fig. 1.

1 is the figure of a woman attired in a traveling suit and represented as facing the observer. In her left hand there is an umbrella 15 2 and in her right hand there is the open scroll 3.

4 is an approximately square field or background representing the ground upon which

the figure stands and serving as a firm support for the latter when the sign is erected by itself in a field or other suitable place. The scroll 3 is of such proportions that it offers a field for the advertisement or inscription which the sign is to carry. 20

The leading feature of my design for a sign consists in the figure of a woman carrying a scroll which forms the field for an advertisement or inscription. 25

What I claim is— 30
The design for a sign-board herein shown and described.

In testimony whereof I affix my signature in presence of two witnesses.

SILAS WEST.
